SEWING MACHINE

Bernard A. Schmitt, Chicago, Ill.

Application August 6, 1945, Serial No. 609,116

9 Claims. (Cl. 112—210)

1

This invention relates to sewing machines of the household type and more particularly to novel drives for stitch-forming and feed mechanisms therefor together with improvements in stitch-length adjusting means.

It is a general object of the present invention to provide a novel and improved household sewing machine.

More particularly, it is an object of the invention to provide, in a sewing machine of the type described, novel and improved drive means for rotary stitch-forming mechanism of the one-to-one ratio type whereby variable speed motion thereof is effected during each revolution as required for cooperation with the needle and for the proper looping of the needle and bobbin threads.

Another important object of the invention consists in the provision of unique means for providing from the variable speed rotary hook drive shaft the horizontal component of motion for the feed dog.

A still further object of the invention consists in the arrangement of novel stitch length-adjusting means whereby the driving connection between the rotary hook drive shaft and the feed shaft may be regulated to result in the desired length of stitch.

An important feature of the invention resides in actuation of the feed shaft from the variable speed hook drive shaft through the agency of a cam and followers.

Another important feature of the invention resides in the drive between the main shaft and the rotary hook drive shaft which eliminates most of the usual vibration by dispensing with the customary crank on the main shaft.

Other and further features and objects of the invention will be more apparent to those skilled in the art upon a consideration of the accompanying drawings and following specification wherein is disclosed a single exemplary embodiment of the invention with the understanding that such changes and modifications may be made therein as fall within the scope of the appended claims without departing from the spirit of the invention.

In said drawings:

Fig. 1 is a front elevation of a sewing machine constructed in accordance with the present invention, certain portions of the frame casting being broken away to permit illustration of the interior working mechanism;

Fig. 2 is a bottom plan view of the machine of Fig. 1;

2

Fig. 3 is a vertical section taken on broken line 3—3 of Fig. 1 looking in the direction of the arrows;

Fig. 4 is a left end elevation of the bed plate and mechanism beneath it;

Fig. 5 is a fragmentary vertical section taken on line 5—5 of Fig. 1 and illustrating the feed shaft connecting-rod drive, and

Fig. 6 is a fragmentary horizontal section on line 6—6 of Fig. 3, looking in the direction of the arrows and illustrating the pivoted fulcrum for the main drive connecting-rod.

In order that a household sewing machine may be commercially successful it should be low in cost, compact, light weight and simple in operation, as nearly vibrationless as possible, and it should operate with ease and quietness. To maintain low cost the machine must be of few parts and these must be of simple construction

requiring the minimum of machining and adjustment during assembly. Quietness, lack of vibration and ease of operation flow from accuracy, good design, careful balance and a reduction in the number of parts, bearings and the like. The

machine of the present invention is unique in combining all of these important functions, and while it has been shown with plain bearings and other simple constructional features it can, where cost is of less importance, be equipped with ball or roller bearings to further reduce the effort necessary to drive it and to decrease the requirements for periodic lubrication. The machine illustrated is incomplete in that no mechanism is shown in the head other than a rudimentary needle bar.

No invention lies in unillustrated portions of the machine and they are assumed to be of conventional construction.

Referring now to the drawings, and particularly Fig. 1, it will be seen that the conventional bed plate 10 is equipped with an integrally cast hollow standard 12, supporting the integral horizontal arm 13 mounting the head 14 in which the needle bar 15 is reciprocated by suitable mechanism. Appropriately journaled in the head is the horizontal main shaft 17 comprising a simple straight rod with no cranks or the like whereby it may be inserted through the end bearing 16 in an extremely simple manner and then engaged in the head drive. Except for the mechanism in the head 14 it mounts only the single, fully balanced spur gear 19 secured thereto by set screw 20. This gear meshes with one of equal diameter at 21. The hub 22 of gear 21 abuts against boss 23 integral with the standard and horizontally drilled at 24 to receive the stem of a tapered spindle

forming the bearing for the hub 22. The spindle is adjustable in the bore 24 by means of the screw shown to provide take-up for wear and to simplify initial assembly and adjustment.

A simple crank-pin having a conical head 26 is bolted into the disc of the gear 21 eccentric to the bearing thereof and forms the upper connection for the main driving connecting-rod 28.

This connecting rod 28 is adapted to drive the rotary hook drive shaft 30 extending longitudinally of the machine beneath the bed plate and having bearings at opposite ends in bearing members 31 and 32, respectively, which are integral with or suitably attached, as shown, to the underside of the bed plate. This horizontal shaft drives the vertical shaft 34 of the rotary hook or stitch-forming device 35 through suitably meshed, one-to-one ratio, spiral gears 36 and 37. The vertical shaft 34 is journalled in forks 38 and 39 of the bearing member 31 suitably positioned to locate the rotary hook entirely to the right of the needle axis.

The details of the stitch-forming mechanism are reserved for separate applications for patent, but it should be pointed out here that stitch-forming mechanism of the rotary, one-to-one ratio, vertical-axis type requires non-uniform or variable speed drive so that at portions of the rotation of the mechanism the speed is materially reduced to permit the entrance of the needle and the looping of the needle and bobbin threads. This irregularity of drive is achieved through the connection between the main shaft and the rotary hook drive shaft 30 by way of the connecting rod 28, which connection will now be described.

The shaft 30 has pinned to it, on the right side of bearing 32, an arm 41 slotted radially as at 42, seen best in Fig. 3, and in this slot fits a block 43 pivoted at 44 on the lower end of connecting rod 28. Intermediate the ends of the connecting rod and substantially closer to the lower end is a fulcrum for the same comprising grooved block 45, pivoted on a horizontal shaft or stem 46, freely journalled in bushing 47 adjustably held in clamp 48 intermediate the ends of bridge 50 extending across the opening 51 in the bed plate beneath the standard.

Reference should be had to Fig. 6 for the detail construction of this assembly. The connecting rod 28 will be seen to have tapered or converging sides which slide in the similarly shaped channel or groove in the block 45 whose integral stem 46 is seen in bushing 47. It will be appreciated that wear between the connecting rod and the walls of the groove 45 can be compensated for by adjusting the bushing 48 toward the head of block 45, the under surfaces of which bear on the left end of the bushing. Since the connecting rod does not bottom in its groove this insures against any lateral play and eliminates noise as well as permits compensation for wear and simplifies initial adjustment.

If desired, the block 43 and the groove 42 in arm 41 may be similarly arranged. It will be appreciated that proper design of the connections just described will permit the desired non-uniform motion of the rotary hook drive shaft.

The rotary hook drive shaft 30 extends to the left beyond the gear 36 and is there fitted with a tapered eccentric 50, having a collar 51 integral therewith and adjustable on the shaft longitudinally and locked in position by a set screw as shown. This eccentric is straddled by the arms of fork 54 on one end of feed dog carrier 55, whereby a vertical component of motion is contributed so

that the feed dog 56, suitably attached to the carrier, may be projected above and withdrawn beneath the surface of the bed plate for feeding the fabric beneath the presser foot for cooperation with the needle. The feed dog operates in a suitable slot, not shown, in the bed plate.

The horizontal component of movement for determining the length of stitch is imparted to the opposite end of the feed dog carrier 55 by means of feed shaft 60, mounted to the rear of and somewhat above the rotary hook drive shaft 30. This shaft is mounted for rocking or oscillation between depending bosses 62 and 63 on the underside of the bed plate. The pivots are adjustable and one may be tapered as shown. This shaft 60 at its left end mounts a pair of upwardly projecting arms between which is journalled the elongated transverse head 64 on the rear end of the feed dog carrier 55. The wide spacing of the arms 66 insures against any lateral movement of the carrier 55 so that the forked end is constrained to move in a plane and traverse an appropriate path on the tapered surface of the eccentric. Longitudinal adjustment of the eccentric takes care of wear on the forks and eccentric surface so that a tight fit is always insured.

Oscillation is imparted to feed shaft 60 through the agency of a substantially horizontal connecting rod 68 pivoted at 69 to the lower end of a vertical lever arm 70 extending downwardly from the shaft 60. The enlarged opposite end 71 of the connecting rod fits over the tapered heart-shaped cam 72 mounted for rotation with the shuttle shaft 30.

The connecting rod is preferably a sheet metal stamping so instead of being forked the upper end is closed as shown for greater strength and lightness and has inturned, opposed, straight flanges 73 forming the followers for the cam. These flanges conform to the taper of the cam and are parallel to the axis of the connecting rod as shown. The taper of the cam is for the same purpose as the taper in eccentric 50, to provide for simple initial setting and adjustment for wear by longitudinal movement of the cam.

If the connecting rod were free on the cam it is clear that it would not impart any movement to arm 70 and shaft 60 because of the parallel disposition of the flanges 73 to the axis of the connecting rod. If, however, restraint is given to the vertical movement of the head of the connecting rod, then a horizontal component may be imparted to its motion. Such restraint is effected by means of link 75 pivoted to the enlarged head near its upper left hand corner as viewed in Fig. 5 as at 76. The link is short and its opposite end is carried on a fulcrum 78. It will be clear that if this fulcrum is positioned so that the link is substantially parallel to the flanges 73 that no motion will be imparted to the feed shaft, but if, as shown, the link has an angle of greater than zero and less than 90° with the axis of the connecting rod then some of the vertical movement imparted to the head by the cam is converted into horizontal movement. By changing the position of the fulcrum 78 the amount of movement imparted to the feed shaft is regulatable, and this provides a simple means for manually adjusting the length of stitch or the quantity of fabric fed per stroke of the feed point.

In order to control the path of movement of the adjustable fulcrum 78 it is also attached to one end of a second link 79 of substantially the same length as link 75. The opposite end of link 75 79 is fulcrumed at 80 on boss 81 extending from

bearing member 32. This boss is so positioned that the pivot 80 is substantially in alignment with pivot 76 in one of the intermediate positions of the connecting rod head. The path of the fulcrum 78 will be seen to be confined to an arc having a radius equal to the length of link 79. Movement within this arc to the desired degree is effected by means of a positioning link 85 best seen in Fig. 3. It is journaled on fulcrum 78 and its opposite end is pivoted at 86 intermediate the ends of an adjusting lever 87. The inner end of this lever is fulcrumed on a boss 88 on the inner wall of the standard by means of a screw 89 and spring washer for providing friction to hold the lever in any position set. The outer end of the lever provides for finger tip adjustment and extends through a slot 90 in the front wall of the standard and passes alongside of graduations, not shown, on the slotted cover plate 91, for designating the length of stitch.

The solid lines in Fig. 3 show the maximum adjustment of the fulcrum 78 in one position and the dotted lines in the opposite. Intermediate these two positions is the point of substantially zero movement of the said shaft so that both forward and rearward movements can be imparted to the feed dog from zero to maximum stitch length.

The mechanism just described provides a simple means for driving the feed shaft to the extent desired from a parallel shaft having full rotation but irregular motion. The adjusting lever effects both changes in stitch length and reversal of direction of cloth feed by changing the amplitude of oscillation of the feed shaft and its phase in relation to the variable speed rotary shaft.

I claim:

1. In a household type sewing machine, in combination, a bed plate, a standard, an arm and a needle-bar supporting head, a main shaft extending through the standard and arm into the head, a rotary hook drive shaft extending beneath the bed plate parallel to the main shaft, means to drive said hook drive shaft with a one-to-one ratio from the main shaft, an oscillatable feed shaft substantially parallel to the hook drive shaft, a cam on the hook drive shaft, a connecting rod having straight, opposed follower surfaces engaging said cam in planes parallel to the axis of the rod, means pivoting the opposite end of said rod to an arm on said feed shaft, an eccentric on said hook drive shaft, a feed dog carrier having a fork at one end engageable with said eccentric and having the opposite end pivoted to an arm on said feed shaft, a link pivoted to said connecting rod near one of said follower surfaces, a fulcrum for the opposite end of said link and means to adjust the position of said fulcrum to vary the amount of axial movement imparted to said rod by said cam.

2. The sewing machine as claimed in claim 1 in which the drive between main and rotary hook drive shafts includes a crank separated from the main shaft by a gear train.

3. In a sewing machine, in combination, a straight main shaft, a rotary hook drive shaft adapted to be driven at a one-to-one ratio from the main shaft, a slotted arm on said hook drive shaft, a connecting rod having a pivoted block on one end thereof slidable in said arm, an intermediate fulcrum for said connecting rod having longitudinal sliding engagement therewith, a crank disc driving the opposite end of said

connecting rod and having a toothed periphery and a gear on said main shaft meshing with said disc.

4. In a sewing machine in combination, a bed plate, a standard, an arm and a head, a main shaft extending through said standard and arm and into said head to drive a needle-bar, a rotary hook drive shaft journaled beneath the bed plate and having a radially slotted member on the end thereof beneath the standard, a gear journaled on an axis parallel to said shafts, a spindle for said gear carried by a wall of said standard, a gear on the main shaft meshing with the first gear, an eccentric pin on said first gear, a connecting rod having one end pivoted on said pin and having a block on the opposite end slidable in said slotted member, a fulcrum member mounted from said bed plate on a horizontal axis, said member having a slot and said connecting rod being arranged to slide in said slot to rotate the hook drive shaft in the opposite direction and at a non-uniform speed from said first gear.

5. The sewing machine as claimed in claim 4 in which the fulcrum slot has converging sides, the connecting rod has a corresponding cross-section and means is provided to hold the fulcrum in various positions relative to the rod, whereby it may be adjusted for initial fit and to compensate for wear.

6. In a sewing machine, in combination, a bed plate, a standard thereon, an arm extending from the standard and supporting a head, a rotary main shaft extending through the standard and arm and into the head, a feed shaft pivoted for oscillation beneath the bed plate at the rear thereof, an arm on said feed shaft adapted for oscillation therewith about a vertical position, a rotary hook drive shaft rotatably mounted beneath the bed plate near the front thereof, means to drive said last mentioned shaft at a one-to-one ratio from the main shaft but at a variable angular speed, a cam on the rotary hook drive shaft, a connecting-rod having one end pivoted to said arm and having an enlarged opposite end provided with an opening loosely receiving said cam, said opening having two opposite sides disposed parallel to the axis of the rod and engaging the cam as followers, a link pivoted to said enlarged end, a movable fulcrum for the opposite end of said link and means to constrain the path of movement of the fulcrum to an arc bisected by a line through the link pivoted and parallel to the axis of the rod.

7. In a sewing machine as defined in claim 6 in which the fulcrum-constraining means is a second link extending between the fulcrum and a fixed pivot.

8. In a sewing machine, in combination, a bed plate, a standard thereon, an arm extending from the standard and supporting a head, a rotary main shaft extending through the standard and arm and into the head, a feed shaft pivoted for oscillation beneath the bed plate at the rear thereof, an arm on said feed shaft adapted for oscillation therewith about a vertical position, a rotary hook drive shaft rotatably mounted beneath the bed plate near the front thereof, means to drive said last mentioned shaft at a one-to-one ratio from the main shaft but at a variable angular speed, a cam on the hook drive shaft, a connecting rod having one end pivoted to said arm and having an enlarged opposite end provided with an opening loosely receiving said cam, said opening having

two opposite sides disposed parallel to the axis of the rod and engaging the cam as followers, a link pivoted to said enlarged end, a movable fulcrum for the opposite end of said link, a guiding and supporting means for said fulcrum comprising a second link pivoted to said fulcrum, a stationary pivot for the opposite end of said second link, a hand lever pivoted to said standard and extending forward through a slot in the same, and a link extending from said fulcrum to an intermediate point on said lever.

9: A sewing machine of the type described comprising in combination, a uniform speed main shaft arranged to actuate a needle bar, a non-uniform speed rotary shaft arranged to actuate a rotary hook, a feed shaft mounted for oscillation and arranged to act in combination with said non-uniform speed rotary shaft to actuate the cloth feeding device of the sewing machine, means to oscillate the feed shaft from the non-uniform speed rotary shaft, means to

adjust the amplitude of oscillation of the feed shaft, and said last mentioned means being arranged to change the phase of oscillation of the feed shaft in respect to the rotation of the non-uniform speed rotary shaft.
